CLAIM

The ornamental design for a money counter, as shown and described.

DESCRIPTION

1. Money counter

1.1 : Perspective

1.2 : Back

1.3 : Front

1.4 : Side view

1.5 : Top view

The reproductions depict a device for counting money; the views consist of 1.1; perspective, front view; 1.2: back view; 1.3: front view; 1.4: side view and 1.5: top view; one side view is omitted because it is a mirror image of side view 1.4.
